[57] **CLAIM**

The ornamental design for a mobile telephone and office accessory stand for mounting in the interior of a vehicle, as shown and described.

DESCRIPTION

FIG. 1 is a front elevational view of the mobile telephone and office accessory stand for mounting in the interior of a vehicle showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view with the office accessory items shown in broken lines for convenience of illustration and forming no part of the claimed design.

FIG. 1

FIG. 2

FIG. 3

FIG. 4

FIG. 5

FIG. 6

FIG. 7
